UNITED STATES PATENT OFFICE.

LAWRENCE ERVIN HUBBARD, OF TORONTO, ONTARIO, CANADA, ASSIGNOR TO THE TABULATING MACHINE COMPANY, OF ENDICOTT, NEW YORK, A CORPORATION OF NEW JERSEY.

TABULATING MACHINE.

Application filed May 10, 1922. Serial No. 559,728.

To all whom it may concern:

Be it known that I, LAWRENCE ERVIN HUBBARD, a citizen of the United States, residing at Toronto, Province of Ontario,

5 Dominion of Canada, have invented certain new and useful Improvements in Tabulating Machines, of which the following is a full, clear, and exact description.

In the tabulating of statistical data it is now the common practice to use tabulating machines which are adapted to take off records from perforated cards. In operations of this sort, the individual cards are perforated or punched in different locations 10 to denote the desired record items. These items may represent amounts, group numbers, classes, numbers of workmen, wages due, and, in fact, any desired data which is desired to be recorded or accumulated. 15 These cards, after being sorted, are placed in tabulating machines which advance the successive cards therethrough and accumulate the aggregates of certain items and indicate or otherwise display the classifying group 20 numbers. After the tabulation of a group is completed it is the common practice to terminate or suspend the tabulating operation, take a reading either visually or by suitable recording means, reset one or more of the tabulator counters or registers to zero and then 25 initiate a new tabulating operation. The termination of the tabulating operation is usually controlled by a so-called stop card and in certain instances by automatic control devices which are controlled from the 30 index points of the cards designating the group numbers. The initiation of a new tabulating cycle automatically has heretofore been proposed but such devices are not 35 adaptable to control an ordinary tabulating machine to permit an extended reading interval between operations which may be varied to suit different operating conditions.

The present invention is directed to the provision of a single attachment for a tabulating machine which will permit the machine to suspend operations at the end of a tabulating operation for a short time interval to permit a reading to be taken and thereafter to cause the machine to commence tabulating automatically.

Further objects reside in the provision of a device of this character so arranged that the reading or dwell time may be adjusted to meet the exigencies of a particular

tabulating operation or to correspond with the skill, lack of skill, or speed of any particular operator of the machine.

While the invention finds particular utility in connection with non-printing tabulators, 60 its use is not limited to machines of this type and the attachment may be applied to printing tabulators.

Other objects and advantages will be hereafter pointed out in the accompanying specification and claims and shown in the drawings in which:

Fig. 1 shows a front view of a tabulator to which the attachment may be applied.

Figs. 2 and 3 are details of the relay and 70 controlling means which controls the period of dwell or hesitation between two tabulating operations.

Fig. 4 is a diagrammatic view showing the electric circuits and certain mechanical 75 details of the machine.

The present invention will be explained with particular reference to Fig. 4 which shows a diagrammatic view of a Hollerith tabulator embodying my invention. In this 80 view counters A and B are of the type usually used in tabulators of this class and the counter A is utilized for group indicating purposes and the counter B is utilized for accumulating. It will be understood 85 that any number of counters may be used as desired. In Fig. 1, for example, five counters, A, B, C, D, E, are shown.

In order that the present invention will be clearly understood a brief description 90 will be given of the main features of the tabulator shown in Fig. 4. In this figure, 10 designates a stack of record cards which are fed one by one through upper and lower feed rolls 11 and 12 past cooperating brushes 95 13 and contact blocks 14. The usual card lever 24 is provided which upon the passage of cards is adapted to close the card contacts 25. The gearing for rotating the feed rolls is shown conventionally at 18. This 100 gearing receives its drive from a shaft 20 which, by a belt and pulley connection is driven by tabulator motor 21. A shaft 22 forms the main drive shaft to the tabulator counters and is shown broken away in the 105 upper part of Fig. 4 and extended into cooperation with the two tabulator counters in the lower part of the figure. A similar shaft 23 driven in unison with the card feeding devices operates a number of cam 110

contact devices 32, 33 and 34. These cam contact devices are those usually used in tabulators of this class. The cam contact combination 32 is the so-called motor cam which interrupts the circuit to stop the machine. The make and break combinations 34, 33 control the card brush circuits.

To start the tabulator in operation the operator places a number of cards in the stack and then closes switch 26 which establishes circuits to the current supply mains. The start key 27 is now depressed. Current flows from the source through line 28, start key 27, motor relay 29, tabulator motor 21 through emergency stop key 30, now closed, and back to other side of line. The tabulator motor now rotates. Coincidently with the establishment of the aforementioned circuit through motor relay 29 a second circuit is established through a line 60 and a so-called hesitation relay 61 and back to the other side of line through the stop key. The energization of the relay 61 opens up the so-called resetting circuit for the resetting motor of the tabulator and prevents resetting until certain other conditions arise. The energization of the motor relay 29 also establishes a holding circuit which permits the release of the start key 27. This circuit may be traced as follows: through line 28, cam contact combination 32, now closed, wire 31, armature of relay 29, relay magnet 29 and back to the other side of the line through the path previously traced. The tabulator is now in operation and as the perforations in the cards successively pass under the controlling brushes the counter magnets 44 are energized thereby attracting their armatures 45 and releasing the clutch levers 46 which are actuated to engage the clutches 48 in the manner described in the patent to Lake No. 1,307,740. The items from the cards are then accumulated or indicated on the counters in the usual manner. During this tabulating operation and so long as cards are passing through the machine and card lever contacts are closed, motor control relay magnet 37 and counter control relay magnet 36 will be energized. The attraction of the armature of motor control relay 37 establishes another holding circuit for the tabulator motor through a line 38 and the armature of relay 29 and through the path previously traced. This holding circuit maintains the tabulator in operation when the cam contacts 32 break once per card cycle. The purpose of the cam contacts 32 is to interrupt the tabulating operation upon the de-energization of the motor control relay 37 after the last card has passed through the machine and permitted contacts 25 to open. The energization of counter control relay 36 attracts its armature and closes a circuit 40 supplied from the make and break contacts

33, 34. From wire 40 current flows through the armature of relay 36, thence through line 41 to the common brush bar 17. The tabulating operation continues until after the last card or until a stop card passes the card lever 24, then the card lever swings and opens up contacts 25. This opening of these contacts interrupts the circuit through motor control relay 37, counter control relay 36 and card brush circuit. The deenergization of motor control relay 37 breaks one holding circuit for the tabulating motor 21. Thereafter upon the opening of cam contacts 32 the other holding circuit through the armature of relay 29 is interrupted and this relay is deenergized thereby bringing the tabulator motor 21 to a stop.

Upon the stoppage of the tabulator motor the operator may read the totals or other designating numbers from the tabulator counter wheels. A reading of the tabulator counters is then to be taken, thereafter the counters are to be reset and a new tabulating operation upon a new card group commenced. In order to provide a sufficient interval of time for the reading of the counters prior to the resetting, and the initiation of a new tabulating cycle, the hesitation or dwell relay 61 is provided. The armature 62 of this relay is connected through a link 63 to a piston 64 which is mounted to move back and forth in a cylinder 65 (see Fig. 3). Upon the attraction of the armature 62 the piston 64 may move rapidly upward in the cylinder 65 by reason of a small check valve 66. Upon the de-energization of the magnet 61, the piston 64, together with its interconnected armature, descends slowly by gravity. The dash pot device constitutes a means associated with the relay for maintaining a period of dwell during which the tabulator is at rest.

The length of time required for its descent and the re-establishment of the circuit of contacts 67 may be varied by means of the adjusting screws 68. The time of descent of the dash pot piston and its interconnected armature is sufficient to permit the operator of the tabulator to read and write down on a suitable record the readings from the tabulator counters. This time is entirely independent of any times of the operation of the tabulator or of the resetting means therefor. Upon the re-closure of contact 67 a resetting circuit is established which is traced as follows, on Fig. 4. Switch 69 having been previously closed, current flows from source to binder post R¹ through switch 69, wire 70, armature 62, contacts 67, wire 71, binder post R³, reset magnet 72, binder post R⁴, reset motor 73, binder post R⁵ and back to source. The energization of magnet 72 energizes the magnetically controlled reset clutch 74 and

clutches motor 83 to the resetting shaft 75 of the tabulator. The energization of magnet 72 also closes contacts 76 which establishes another circuit to binder post R² and 5 to magnet 72. This circuit is only necessary when switch 69 is opened and the resetting initiated by the depression of the reset key 77. The reset motor circuit slightly later in the cycle is taken over by 10 cam contact devices 78 which short-circuits the magnet 72 and interrupts the reset motor circuit at the end of the reset cycle. The magnetically controlled clutch 74 is of the usual one revolution type and insures the 15 shaft 75 making exactly one revolution in resetting. Just before reset cycle is completed the cam contacts 79 are closed, thereby establishing a circuit from binder post R¹ through cam contacts 79, binder post 20 R² to motor relay 29. The establishment of this circuit automatically restarts the tabulator in its tabulating operation as previously described. This restarting of the 25 tabulator energizes the hesitation magnet 61 and opens the contacts 67, hence preventing any further resetting until the tabulating of this new group of cards is again completed.

In diagrammatic Fig. 4, magnet 72 is shown in full line position and in dotted line position. This method of illustrating is utilized for sake of clearness in the wiring diagram. In other words, the magnet 72 both controls the reset clutch 74 and also controls the contacts 76.

35 What I claim is:—

1. An attachment for a tabulating machine having the usual counters and means for driving and resetting the same, said attachment comprising in combination, means 40 for interrupting the tabulating operation at the end of a card group, means independent of speed of operation of the tabulating or resetting means for maintaining a dwell in the position of the counters to permit a reading to be taken therefrom of the

items received from the preceding tabulation, means for thereafter automatically initiating a new tabulating operation upon a new card group.

2. An attachment for a tabulating machine having a driving motor comprising a delayed action relay with controlling means associated therewith for suspending the tabulating operation, means associated with said relay for maintaining a period of 50 dwell to permit a reading to be taken, and means controlled by said relay for automatically initiating a new tabulating operation.

3. The invention set forth in claim 2 in which means is provided for varying the 60 time of dwell in which readings are to be taken.

4. An attachment for a tabulating machine having the usual counters and driving and resetting means therefor, means for interrupting the tabulating operation at the 65 end of a card group, in combination therewith, means operating independently of the timing or speed of the tabulator driving means or resetting means for maintaining a 70 period of dwell in the tabulating operations for a determined period to permit counter readings to be taken, means for varying the time of said dwell, means for automatically initiating a new tabulating operation after 75 said determined period of dwell.

5. The invention set forth in claim 4 in which means is provided for automatically effecting a resetting of the tabulator counters to zero after the taking of a reading and prior to the initiation of a new tabulating cycle.

6. The invention set forth in claim 4 in which the means for controlling and varying the time of reading dwell comprises a 80 relay and a controlling dash pot.

In testimony whereof I hereto affix my signature.

LAWRENCE ERVIN HUBBARD.
